UNITED STATES PATENT OFFICE.

THOMAS BENFIELD, OF NEWARK, NEW JERSEY.

DESIGN FOR A WATCH-CASE.

SPECIFICATION forming part of Design No. 21,481, dated April 19, 1892.

Application filed March 17, 1892. Serial No. 425,364. Term of patent 7 years.

To all whom it may concern:

Be it known that I, THOMAS BENFIELD, a subject of Her Majesty the Queen of Great Britain, residing at Newark, in the county of 5 Essex and State of New Jersey, have invented and produced a new and original Design for Watch Cases, of which the following is a specification, reference being had to the accompanying drawings, forming part thereof.

10 Figure 1 is a plan view of a watch-case, showing my new design. Fig. 2 is a sectional view thereof, taken on a line X X of Fig. 1.

The leading feature of my design consists of a series of corrugations or ribs A, convex 15 in cross section, as shown in Fig. 2 of the drawings, said ribs being curved in the form of arcs of circles in their length and in oppo-

site directions on either side of the center of the lids, as shown in Fig. 1, the center of the case being left plain, as shown at B. The 20 several portions may, it is manifest, be engraved, chased, or otherwise ornamented, as desired. It is also apparent that other articles—such as, for instance, lockets—may be ornamented with the above-described design. 25

Having described my invention, what I claim as new, and desire to secure by Letters Patent, is—

The design for a watch-case, as herein shown and described.

THOMAS BENFIELD.
